UNITED STATES PATENT OFFICE.

EDWARD GEORGE CARR, OF OCEANSIDE, CALIFORNIA.

CONCRETE-TAMPER.

1,204,245.

Specification of Letters Patent. Patented Nov. 7, 1916.

Application filed June 22, 1915. Serial No. 35,576.

To all whom it may concern:

Be it known that I, EDWARD G. CARR, a citizen of the United States, and a resident of Oceanside, in the county of San Diego and State of California, have invented a certain new and useful Improvement in Concrete-Tampers, of which the following is a specification.

My invention relates to improvements in tamping devices used in constructing concrete roads or beds, and has for an object to utilize the various vibrations of a power driven shaft carrying an eccentrically mounted weight to impart a horizontal motion to one tamper templet or blade and a vertical movement to another templet or blade, either simultaneously or intermittently.

With these and other objects in view, my invention consists broadly in a method of, and apparatus for tamping concrete by a pair of templets or blades, one having a horizontal and the other a vertical movement.

My invention consists further in the method and means of imparting a horizontal and a vertical movement to a pair of templets or blades through the agency of a revolving eccentrically mounted weight.

My invention consists further in certain novel features of construction, arrangement and combination of parts as will be hereinafter described and pointed out in the claims, reference being had to the accompanying drawings, in which:

Figure 1 is a top plan view showing an embodiment of my invention. Fig. 2 is a vertical section on line 2—2 of Fig. 1. Fig. 3 is a section on line 3—3 of Fig. 1. Fig. 4 is a section on line 4—4 of Fig. 1. Fig. 5 is a section on line 5—5 of Fig. 1. Fig. 6 is a section on line 6—6 of Fig. 1. Fig. 7 is a section on line 7—7 of Fig. 1. Fig. 8 is an enlarged section showing one of the clutch members engaged.

In carrying out my invention a suitable frame F is used, mounted on the drive wheels G and the front guide wheels G'. At the forward end of the frame the tamping templets A and A' are suspended, the front templet or blade having a resilient connection with the bearing of the front wheels G' at each side by means of the springs S as shown plainly in Figs. 1, 2 and 3; this templet or blade is also suspended from the frame by the chains I rig-

idly secured to the rock shaft I' in such a manner that turning of said rock shaft by the hand lever L will raise or lower said blade A. Templet or blade A' is also suspended by chains I² rigidly secured to the rock shaft I³ which carries a hand lever L' similar to lever L and manipulated in the same manner; templet or blade A' is also resiliently suspended from frame F by the curved springs S' one end being secured to the frame and the opposite end bent back and secured to the templet or blade A' at or near each outer end, as plainly shown in Fig. 5. The blades A and A' are both also suspended from the shaft B which has a ball and socket bearing B' at one end and adjacent its front the pitman P which is connected to the blade A in such manner as to impart a longitudinal movement to said blade, or across the road bed, when shaft B is revolved; spaced apart from blade A, the blade A' is suspended from shaft B by the solid pitman P' extending upwardly from the shaft and a cross pin P² connecting the angular-brackets P³ spaced apart and secured at their lower ends to opposite faces of said blade A' as shown in Fig. 5; blade A' is further supported by the brace rods K which have a pivotal or hinged connection with the axle of wheel G. Upon shaft B but between the templets or blades A and A' is eccentrically mounted the weight W as illustrated in Figs. 1, 2 and 7; shaft B is driven from the main shaft of the engine by pulleys and belts and a clutch C² on shaft B, the engine used being of any suitable type, and from the crank shaft of the engine power is belted off to a shaft D which has a worm D' meshing with gear D² on the shaft D³ extending across the frame and carrying at its outer end on both sides the sprocket gears D⁴ each carrying a clutch member D⁵ adapted to engage the mating clutch member D⁶ actuated by levers D' when it is desired to throw the engine into and out of gear with the driving wheels of the truck; the said rear wheels G have mounted at their outer sides sprockets G³ to be driven by a sprocket chain G⁴ running over the sprocket on the shaft D; the shaft D, it will be noticed carries means for driving the device forward and reverse or backward, such means in the present embodiment comprising a clutch C and clutch C', the contacting or actuating member C² slid-

ably mounted on shaft D and the lever L² and connecting rods L³ and L⁴; the clutches C and C' are of course operably connected with the belt pulleys driven by the belts 5 which get their motion from the crank or drive shaft of the engine or motor, as indicated in Fig. 1. This tamping apparatus is driven forward and backward with its own power, and the driving mechanism is 10 so proportioned that by use of a reducing pulley on the motor which runs 1 to 4 of the crank shaft, I get different speeds forward and backward; in the present instance the tamper runs forward at rate of seven 15 (7') feet per minute, and then backward at rate of sixty (60') feet per minute, the engine running all the time, but the weight revolving only when the tamper is driven forward.

20 It will be noticed that the tamping templets or blades, are separate and independent and are connected with shaft B in such a manner that one (the rear one A') gets all the vertical jar or vibration, and no 25 horizontal jar, and the other one (the forward one A) gets all the horizontal jar and no vertical jar. Each templet will be about two inches or less in width and does not move more than one inch, but strikes about 30 600 strokes per minute. The clutch D⁵—D⁶ is for the purpose of letting one side of the apparatus go ahead in rounding curves. By means of the chains I and I² and the levers L and L' the templets or blades can be raised 35 and lowered to suit varying circumstances. It will of course be understood that when the device is in use the lower faces of the templets are supported slightly above the upper surface of the road bed upon which 40 it is operating.

The operation of the device is as follows: The apparatus having been placed across the road bed is supported by the wheels G and G' on the tracks R with the templets 45 or blades A and A' slightly above the concrete in its mastic state; the shaft B is now thrown into gear with the crank shaft of the engine which may be constantly running; the shaft B is now given a high number 50 of revolutions and the weight W being eccentrically mounted on said shaft will cause horizontal jars to be imparted to the front templet A through the pitman P, and at the same time vertical jars or vibrations 55 to the second templet or blade A' through the pitman P' and bracket P², the entire device meanwhile moving forward at the rate of about seven feet a minute and then being run backward at about the rate of 60 sixty feet a minute; the operation is repeated along the road bed until completed. Both templets or blades receive a yielding or resilient motion through the agency of the springs S and S'. It will thus be observed 65 that I effectually tamp the concrete

bed by peculiar motion of a pair of templets, moving simultaneously along the bed but one templet vibrated horizontally only, while the other is vibrated vertically only.

I claim:—

1. The herein described method of tamping concrete beds consisting in suspending a pair of spaced apart independent templets or blades slightly above said bed, and imparting the horizontal vibrations of an unbalanced revolving shaft to one of said templets and the vertical vibrations of the said shaft to the other of said templets. 70

2. The herein described method of tamping concrete roads or beds consisting in suspending a pair of independent tamping blades slightly above the bed and simultaneously imparting a horizontal vibratory motion to one blade and a vertical vibratory motion to the other blade. 80

3. The herein described method of tamping concrete beds consisting in suspending across said bed a pair of independent tamping blades, mounted to travel forwardly and backwardly along the bed, and imparting a horizontal vibratory motion only, to one of said blades and a vertical vibratory motion only, to the other of said blades, said vibratory motions being imparted only during the forward travel of said blades. 85

4. The herein described method of tamping concrete beds consisting in yieldingly suspending a pair of spaced apart tamping blades slightly above said concrete bed and simultaneously translating the horizontal vibrations of a rapidly revolving weighted shaft to one of said blades and the vertical vibrations of said shaft to the other blade. 100

5. The herein described method of tamping concrete beds consisting in translating the vibrations of an unbalanced revolving shaft to a pair of spaced apart tamping templets suspended in parallel planes, the vibrations imparted to one templet being directed in a horizontal direction and the vibrations imparted to the other templet being directed in a vertical direction, the vibrations being imparted only during a forward travel of said templets along the concrete bed. 105

6. In a concrete tamper, the combination with a pair of independently supported spaced apart tamping templets or blades, and means for imparting horizontal vibratory motion to one templet or blade, and vertical vibratory motion to the other blade. 110

7. In a concrete tamper, the combination with a pair of spaced apart yieldingly suspended tamping templets or blades, and means for imparting a horizontal vibratory motion to one of said templets, and a vertical vibratory motion to the other templet. 120

8. In a concrete tamper, the combination with a pair of spaced apart independently suspended tamping templets, means for 130

movably supporting said templets above a road bed and across the same in shaking contact therewith, and an unbalanced motor carried by said supporting means and means for translating the vibrations of the motor to the templets in horizontal and vertical directions respectively.

9. A concrete tamping device comprising in combination, a wheeled frame disposed across a road bed and adapted to travel forwardly and backwardly thereon, a motor mounted thereon, an eccentrically weighted shaft driven by said motor, a pair of spaced apart tamping templets independently suspended from said frame, and means operably connected with said weighted shaft for imparting vibrations set up by said weighted shaft, the vibrations imparted to one templet being in a horizontal direction, and the vibrations imparted to the other templet being in a vertical direction.

10. A concrete tamping device comprising in combination, a wheeled frame disposed across a concrete road bed and adapted to travel forwardly and rearwardly thereon, a motor mounted thereon, a shaft revolved by said motor, a weight eccentrically mounted on said shaft, a pair of spaced apart independently and yieldingly suspended tamping templets carried by said frame across the road bed and connections between the shaft and each templet whereby the vibrations of the said shaft are translated to the pair of templets, the vibrations imparted to one templet being in a horizontal direction and the vibrations imparted to the other templet being in a vertical direction.

11. In a concrete tamper adapted to tamp concrete road beds, the combination with a wheeled frame disposed across the road bed and adapted to travel forwardly and rearwardly thereon, a motor supported on said frame, means for driving the wheeled frame from the motor, a pair of spaced apart tamping templets, yieldingly and independently suspended from said frame and in shaking contact with the road bed, a weighted shaft revolvably driven from said motor, a pitman connecting the weighted shaft with the tamping templets respectively whereby the horizontal vibrations of the weighted shaft are transmitted to one of the templets and the vertical vibrations of

shaft are simultaneously transmitted to the other templet.

12. In a concrete tamper, the combination with a wheeled carriage adapted to be mounted across a concrete road bed, a pair of spaced apart tamping templets yieldingly and independently suspended from said carriage across the road bed, a motor mounted on said carriage, an eccentrically weighted shaft revolvably driven by said motor, pitman means connecting said shaft with the spaced apart templets respectively to impart a horizontal vibratory motion across the road bed to the forward templet and vertical vibratory motion to the other of said templets.

13. In a device for tamping concrete road beds, the combination with a wheeled carriage disposed across said road bed and adapted to be automatically propelled forwardly and rearwardly, the forward speed being less than the rear speed, a pair of spaced apart tamping templets yieldingly and independently suspended from said carriage across the road bed, a motor carried by said carriage and adapted to propel said carriage, and means for imparting a vibratory motion horizontally to the forward templet and a vertical vibratory motion to the rear templet, said vibratory motions being imparted only during the forward travel of the carriage.

14. In a concrete tamper adapted to tamp concrete road beds, the combination with a wheeled frame disposed across the road bed and adapted to travel forwardly and rearwardly thereon, a motor supported on said frame, means for driving the wheeled frame from the motor, a pair of spaced apart tamping templets yieldingly and independently suspended from said frame, a revolvable shaft moving eccentrically in a circle and driven by said motor, and a pitman connecting the said shaft with the templets respectively whereby the horizontal vibrations of said shaft are transmitted to one of the templets and the vertical vibrations of said shaft are simultaneously transmitted to the other plate.

EDWARD GEORGE CARR.
